UNITED STATES PATENT OFFICE

JOSEPH H. ADAMS, OF BROOKLYN, NEW YORK, ASSIGNOR, BY MESNE ASSIGNMENTS, TO THE TEXAS COMPANY, OF NEW YORK, N. Y., A CORPORATION OF DELAWARE

APPARATUS FOR THE CONVERSION AND TRANSFORMATION OF HYDROCARBONS, LIQUIDS AND FLUIDS

Application filed January 26, 1916, Serial No. 74,337. Renewed January 12, 1929.

This invention relates to a modified and improved apparatus for converting liquids, fluids and oils, more especially those of the hydro-carbon group, into products of lower specific gravity for the purpose of obtaining from high boiling hydro-carbons low boiling products such as naphthas, gasolene and benzine, benzol, toluol and other low specific gravity and boiling products of both the plain and aromatic series as carried on by my process, methods and apparatus as disclosed in co-pending applications Serial Nos. 530,852 filed Dec. 1, 1909; 618,011 filed March 30, 1911; 879,907 filed December 31, 1914; 17,699 filed March 29, 1915 and 53,377 filed September 30, 1915. These applications have eventuated, respectively, in Patents 1,820,354, 1,827,263, 1,820,726, 1,820,727 and 1,445,281.

One object of this invention is to formulate a relatively simple and inexpensive means for applying intense heat under easy control to hydro-carbon oils while under pressure in excess of atmospheric for the purpose of altering their physical and chemical character to a pre-determined extent in order to produce by this means products in greater quantity than presently obtained by the well known methods of fractional distillation or separation processes commonly employed in the art.

Another object in view is to secure simple and inexpensive parts and features which may be easily assembled into a complete system capable of continuously converting hydro-carbons on a commercial basis and in large quantities.

This invention accordingly, consists in the features of construction, arrangement of parts and method of operation which will be more fully indicated in the following description and claims.

Apparatus

In order to completely disclose this invention to those skilled in the art the accompanying drawings, Fig. 1, and Fig. 2, which will illustrate the co-related parts of the apparatus, have been appended and in which the principal features are lettered from A to

F inclusive while like numbers denote corresponding parts throughout the two drawings.

These drawings show side and partly sectional elevations of an apparatus embodying horizontal tubes overlying the upper part of a furnace and through which hydro-carbon liquids or vapors are forced and brought into contact with the intensely heated walls of the tubes for the purpose of transforming them into products essentially different from the original untreated liquids or oils.

This improved apparatus is based on my former inventions particularly co-pending applications 530,852 filed Dec. 1, 1909, 618,011, filed March 30, 1911, 879,907 filed Dec. 31, 1914 and 53,377 filed Sept. 30, 1915, with which I have successfully converted high boiling point hydro-carbons into lower boiling products by means of properly applied intense heats and self generated and maintained vapor pressures to the oil or oily vapors without unduly converting them into large volumes of fixed gases; and by means of this apparatus products of a valuable nature can be obtained from inexpensive original oils and distillates while at the same time increased yields of desirable low boiling hydro-carbons can be had to meet the great demand for them in general commercial usages.

Referring now to the drawings, Fig. 1, the source of supply A, can be somewhat elevated above the principal apparatus or pump, if so desired, to augment the flow of oil into the converting tubes and dome or separator C, under the influence of pressure maintained over the surface of oil in the tank A, or, by means of pump 5, the oil may be delivered continuously into the converting apparatus under pressure greater than that maintained in the system.

Original oil can be admitted to tank A, through pipe 1, regulated by valve 2, and displaced air will escape through pipe 3.

Pipe 3, may be connected with an air compressor or high pressure pump, if desired, to maintain pressure over the surface of oil in tank A, but in general practice I have found

it best to draw oil through pipe 4, by means of pump 5, and force it through pipe 6, into the converter B.

It is best to pre-heat original oil before admitting it to the converting system so that the heat maintained in the furnace B, and converting tubes 11, may be conserved for the more important function of oil and oily vapor transformation.

Both overflow hot oil and waste furnace heat can be applied to this purpose by forcing the original oil through heating coils, as shown at 7, where the waste heat from furnace B, which passes through primary stack 8, before it is exhausted through flue 9, and out into stack 10, pre-heats the ingoing oil to the converting tubes 11.

The drawing shows one of the many forms of tubular converters or stills which may be employed in my oil converting apparatus, and such converter comprises a multiple of tiers of heat enduring tubes 11, constructed of material capable of withstanding intense temperatures and high pressures enclosed within the walls of a furnace B, and designed to maintain therein protracted high temperatures.

The tubular converting tubes 11 are connected in series with terminal fittings and assembled so that each layer or group of tubes will overlie the spaces between those of the layer or group below, in order that the entire nest of tubes may receive the greatest heat efficiency from the heat generated in the underlying furnace and in the path of hot gases passing from the fire box of the furnace to the flue. The terminal or return fittings above referred to are located outside the furnace walls in such positions that they may be readily removed in order to expose the connecting tubes for the purpose of cleaning out any carbon that may have been deposited therein during the cracking process.

At the outgoing end of the series of tubes 11, oil is led into an enlarged carbon collecting device or trap 12, where free carbon, accumulated in the process of oil and oily vapor cracking and transformation is swept by the circulation of oil or oily vapors in the tubes.

This collecting device or trap 12, is provided with a detachable plate 13, for cleaning out purposes, and leading out from the top of this trap, pipe 14, conducts oil and vapors into the horizontal separating dome or chamber C, located at the side of, or above the converting tubes 11.

Any free carbon which may be held in suspense in the oil within pipe 14, may have a chance to precipitate into collecting device or trap 12, so that oil or oily vapors led into separating chamber or dome C, will be partly or wholly freed from mineral carbon.

The separator C, is provided with a false inner bottom or diaphragm plate 15, perforated with holes in which a considerable

number of short stand pipes 16, have been made fast so that oil admitted above this bottom or diaphragm plate 15, must necessarily rise to the top of these tubes 16, before it can overflow into the cavity or basin in the lower part of the separating dome C.

The principal object of the plate 15, and the large number of tubes 16, is to provide greater superficial area for the rapid separation of lighter from heavier oils in vapor form than would be possible from the surface only of a body of oil contained in the dome or separating chamber C and to cause a smaller amount of oil to be contained in the dome between the upper side of the plate or diaphragm 15, and top of tubes 16, due to the considerable number of overflow tubes which displace the greater body of oil and leave only that which is intersticed between these stand pipes 16; thus making it possible to move the oil in a comparatively rapid flow with assurances of a more or less perfect separation of the lighter converted oils and vapors from the heavier partially or wholly unconverted oils.

Overflow oil caught in the lower part of separating chamber C, is led through pipe 17, into the cooling and collecting apparatus D, of which 18 is a cooling coil contained in a tank of cold water and 19 is a trap tank in which the partially cooled oil is collected and from which it is withdrawn through valve 20 into sight box 21 and running tank 22.

From the running tank 22, oil is withdrawn by pump 23 and forced through pipe 100 24 to the tank A for re-treatment as before.

In practice it has been found best to lower the temperature of overflow hot oil passing from the converting tubes and drum C, by flowing it through the coils of apparatus 18 105 before returning the overflow hot oil to the tank A. This can be done by regulating the temperature of water or other cooling medium employed in the tank and in which the coils are immersed. It has been found that heavy oil at temperatures not exceeding 300 to 440 degrees F. can be safely returned to a tank of cool oil but it is more or less hazardous to mingle very hot oil or that in excess of 500 to 600 degrees F. with cold oil as under certain atmospheric conditions it might ignite or cause spontaneous combustion. Therefore, the apparatus 18 will be found convenient and necessary when operating this form of apparatus.

Vapors collected in the upper part of dome C, rise in the tower 25, and are conducted through vapor pipe 26, to the condensing apparatus E, of which 27 are the coils immersed in cold water or other cooling medium which may be the active principle in any form of condenser.

Condensate accumulated in these coils runs into collecting trap tank 28, from which it is withdrawn into running tank F through 130

valve 29, and sight box 30, from which in turn it may be withdrawn by pump 36, as desired.

Vapor pressures generated above a pre-determined degree can be intermittently or continuously exhausted or released through valve 31 in pipe 32 in order to maintain a uniform self generated vapor pressure over the surface of the oil and co-mingled oily vapors within the converting apparatus and which occupies all parts of the system not occupied by liquid hydro-carbons.

Such vapor pressures can be registered in gauges 33, 34 and 35, which, under normal operative conditions, should all indicate the same uniform pressure throughout the system, that is, the vapor pressures which the oils and oily vapors are undergoing in this conversion process.

20 Simplicity in the operation of this apparatus is one of its principal features as well as the rapid, continuous and safe method of oil and oily vapor transformation to produce large yields of low boiling hydro-carbon products to augment the supply from natural sources.

The multiplicity of tubular converters presents large surfaces to the furnace heats in proportion to the amount of oil contained in 30 the tubes provided the ratio of heating surfaces to the quantity of contained oil is in favor of the former.

This result can always be obtained by increasing the number of tubes having the comparatively small diameter of from three to twelve inches, and by so arranging the tubes in the furnace that the proportion of heated surface is from four to six or more times greater than that part of the tube extending 40 through and beyond the walls of the furnace for terminal or return fittings.

The continual flow of oil through the tubes in a relatively small stream permits the intense heat to act rapidly and convert high percentages of the subjected oil into desirable products and the small quantity of oil contained within such tubes, overflow pipes, cooling coils and trap tanks lend the same valuable safety feature to this form of apparatus as claimed in some of my co-pending applications, especially Serial Nos. 530,852 and 618,011 heretofore mentioned; for if a break or rupture occurred in any part of the converting apparatus, the fire which might 50 result from such a condition would be confined principally to a few barrels or a comparatively small number of gallons of oil rather than to a still or large tanks full of the material undergoing treatment.

60 The furnace B, may be operated in any convenient manner with coal, fuel oil, gas, electricity or other economical and easily obtainable heat producing medium, but for uniformity in temperature, economy and ease in handling and satisfaction in general results,

a fuel oil burning equipment with burner 37, arranged to deliver oil under pressure atomized with steam or compressed air and a direct low pressure air supply through an underlying pipe or duct 38, gives the best 70 results; for in this method of intense heat generation a natural draught need not be depended upon and no matter what the weather conditions may be the temperature of the furnace and the stability of such generated heat can be depended upon to produce the desired result.

As a feature of safety on this high pressure system, the blow off valve 39, is preferably located at a distance away from the converter, either above or below the condensing coils, which latter are placed in free communication with the converter tubes 11 and dome C, by means of tower 25 and vapor line 26.

In the drawings, Fig. 2, a vertical type of separator chamber or dome is shown where the inner false bottom or diaphragm 15, is supported on a vertical stand pipe or base. This bottom has a cylindrical open top shell 85 or band made fast to its outer edge, and in holes made in the bottom or diaphragm plate 15, a number of stand pipes 16, are securely attached, as in the false bottom plate 15, of Fig. 1.

The top of this cylindrical side and the tubes 16, are the same height from the diaphragm plate 15, so that oil may overflow both the tubes and the sides of the oil containing well, at the same time, for oil entering the separating chamber or dome C, at the bottom through pipe 14, and rising in the stand pipe, designed as a base to the dome, must rise to the top of the tubes 16, and sides of the well before it can overflow into 95 the cavity at the lower part of the dome to be conducted out through pipe 17 to the cooling and collecting apparatus D.

Oil and oily vapors can be delivered through pipe 14 directly into the base of the dome C, when the valve 41 in pipe 40 is closed and the valve 42 is open; but if, for any reason, it is preferable to deliver oil through valve 41 and pipe 40 to the top of the well, then by closing valve 42, this method of overhead delivery can be accomplished.

In the conversion of paraffine gas oils, solar oils, certain heavy grades of fuel oils and the distillates heavier than illuminating oils from almost any crude, it is desirable and preferable to employ the overhead delivery method, so that gases and vapors may pass off from the end of pipe 40, within the dome C, while the heavier partially or wholly unconverted oils may drop into the well to overflow the sides and pipes 16 in order that a more perfect separation will take place within the pipes 16, and in the vapor spaces above the well and between the outer sides of the

catch basin and inside of the shell of dome or separating drum C.

When converting light distillates such as illuminating oils, naphtha still bottoms and low grade naphthas into gasolenes and other low boiling products, it is desirable to feed oil from the converting tubes through pipe 14, into the base of separating drum C, through valve 42 or through valve 41 and pipe 40, so that oil may flow into the top part of the well and so that cracked oil vapors may condense in the oil contained in the well, and when oil therein is overflowing the sides and tubes, the lighter parts will separate out without mechanically carrying over through the vapor lines and condenser, a large portion of partially converted oils and oily vapors.

Both the horizontal and vertical types of separating domes or chambers C have been employed successfully and their choice is but a matter of mechanical preference and adaptability, and, while the former type is generally the easier to handle in the erection of two or more converters of this type, which may be termed units, the latter, for some reason, seems to give the most satisfactory results in the accumulation and separation of low boiling distillates carrying large percentages of desirable products.

30 Mode of operation

Having filled the reservoir tank A with original oil to be converted, the pump 5 is operated to withdraw oil through pipe 4 and force it through pipe 6, then through pre-heater coil 7, and into the converter tubes 11 where it comes in contact with surfaces exposed to the intense heat generated in furnace B.

40 The rise in temperature generates a vapor pressure, as steam in an enclosed boiler, which pressure overlies the surfaces of oil and occupies all spaces in the system not occupied by liquid oil, and which is maintained 45 at a pre-determined degree throughout and during the process operation.

As the oil and oily vapors leave the converting tubes they enter the collecting device or tank 12, where any free carbon may be 50 caught before the oil rises to the separating chamber or dome C through pipe 14.

Heavier partly or wholly unconverted oils overflow the stand pipes 16, which latter are located generously over the surface of the 55 plate 15, and as they flow to the cavity or collecting basin at the under part of the dome C, the lighter or converted oils escape in the form of vapors through the upper part of the dome C and tower 25, then through vapor line 26, and condensing apparatus E, and are finally caught in collecting tank F, in the form of distillates after passing through trap 28, valve 29 and sight box 30.

The heavier oils flow out from the catch 65 basin at the lower part of dome C through

pipe 17, and rise in the cooling coils 18 of apparatus D, then flow into collecting trap tank 19, and are withdrawn into tank 22, through valve 20 and sight box 21, from which they are in turn withdrawn by means 70 of pump 23 and returned to supply tank A through pipe 24 for re-treatment as before.

This continuous method of oil and oily vapor transformation in a multiple tubular converting apparatus, I have found to be one 75 of the most satisfactory of the various forms of converters, as more fully described in my former inventions and co-pending patent applications, heretofore referred to, and in the application of intense heat above that required merely for the vaporization of the particular oil undergoing conversion and in generating and maintaining vapor pressures of several atmospheres for the purpose of holding down the oils and oily vapors undergoing conversion as well as to assist in the actual conversion, the best commercial results have been obtained where the vapor pressure is maintained throughout the converting system from the source of supply through to the 80 end of or beyond the condensing apparatus while the latter is in free communication with the tubular converting apparatus and other parts of the system under equal pressure.

As this form of apparatus designed for my 90 process of hydro-carbon oil conversion as disclosed in my co-pending application 618,011, filed March 30, 1911 is intended to operate continuously and as many minor changes could be made in the above described construction and many widely different embodiments of this invention could be made without departing from the scope thereof with its fundamental and principal features, it is intended that all matter contained in the above 100 description or shown in the accompanying drawings shall be interpreted as illustrative and not in a limited sense.

It is intended also, that the language used in the following claims is to cover all of the generic and specific features of this invention and all statements of the scope thereof which, as a matter of disclosure, should apply to this invention pertaining to an apparatus for the carrying out of my process for 110 transforming high boiling hydro-carbons under the influence of intense heat and self generated and maintained vapor pressures in excess of atmospheric pressure into low boiling and specific gravity products while all parts 120 of the converting system are in free communication with each other as substantially set forth.

What I claim as new and desire to secure 125 by Letters Patent is:

1. Apparatus for converting high boiling hydrocarbon oil into lower boiling products, comprising a tubular oil converter, maintained at a cracking temperature, means for supplying oil to said converter at the top, 130

means for discharging products at the bottom, a carbon and residue collecting device connected to said discharge and extending below the point of discharge, means for drawing off the collected residue and carbon in said device, a separating chamber connected to the upper portion of said collecting device to receive the vapors and oil therefrom, and means for separately drawing off the converted vapors and unconverted oil from said separating chamber.

2. Apparatus for converting high boiling hydrocarbon oil into lower boiling products, comprising a tubular oil converter maintained at a cracking temperature, means for continuously supplying oil to one end of said converter under pressure, means for discharging products at the other end thereof, a carbon and residue collecting device connected to said discharge and extending below the point of discharge, means for drawing off the collected residue and carbon in said device, a separating chamber connected to the upper portion of said collecting device to receive the vapors and oil therefrom and means for separately drawing off the converted vapors and unconverted oil from said chamber.

3. Apparatus for converting high boiling hydrocarbon oil into lower boiling products, comprising a tubular oil converter maintained at a cracking temperature, means for continuously supplying oil to one end of said converter, under pressure, means for discharging products at the other end thereof, a carbon and residue collecting device connected to said discharge and extending below the point of discharge, means for drawing off the collected residue and carbon in said device, a separating chamber connected to the upper portion of said collecting device to receive the vapors and oil therefrom, means for separately drawing off the converted vapors and unconverted oil from said chamber, and means for maintaining substantially uniform superatmospheric vapor pressure in said converter, collecting device and separating chamber.

4. Apparatus for converting high boiling hydrocarbon oil into lower boiling products, comprising a furnace, a tubular converter maintained at a cracking temperature and comprising sections extending through opposite furnace walls and connected by removable fittings to facilitate the removal of carbon deposited in said sections, means for supplying oil under pressure to one end of said converter, means for discharging the heated products at the other end thereof, a residue and carbon collecting device into which said products are discharged extending below the point of discharge, means for removing the residue and carbon collecting in said device, a separating chamber mounted outside said furnace and means for conveying

ing vapors and oil from said device to said chamber.

5. Apparatus for converting high boiling hydrocarbon oil into lower boiling products, comprising a converter, a residue and carbon collecting device into which said converter discharges, means for removing the residue and carbon, a separating chamber provided with a vapor outlet in its upper portion and an oil outlet at the bottom, means for conveying oil and vapors from the upper part of said carbon collecting device to said chamber, means in said chamber above the bottom to receive the oil and vapors supplied from said carbon collecting device the said receiving means being so constructed as to contain a layer of oil of substantially constant depth and being provided with means for permitting the overflow of oil at numerous points into the bottom portion of the chamber.

6. Apparatus for converting high boiling hydrocarbon oil into lower boiling products, comprising a converter, a residue and carbon collecting device into which said converter discharges, means for removing the residue and carbon, a separating chamber provided with a vapor outlet in its upper portion and an oil outlet at the bottom, means for conveying oil and vapors from the upper part of said carbon collecting device to said chamber, means in said chamber above the bottom to receive the oil supplied from said carbon collecting device including a plate provided with short, upwardly extending pipes projecting therethrough to permit the overflow of oil into the bottom portion of said chamber when the oil reaches a certain level.

7. In an oil converter, a separating chamber provided with a vapor outlet at the top and an oil outlet at the bottom, a false bottom or plate extending across said chamber above the bottom, a series of pipes extending a substantially uniform distance upwardly from said plate furnishing overflow passageways and means for continuously supplying to the upper side of said plate intermingled hot oils and vapors to be separated.

8. In an oil converter, a separating chamber provided with a vapor outlet at the top and an oil outlet at the bottom, a false bottom or plate extending across said chamber above the bottom, a series of pipes extending a substantially uniform distance upwardly from said plate furnishing overflow passageways, means for heating oil in a substantially continuous stream under pressure to a cracking temperature, means for separating out carbon and residue from said product and means for discharging the balance of said product into said chamber above said plate.

9. In an oil converter, a separating chamber provided with a vapor outlet at the top and an oil outlet at the bottom, a false bottom or plate extending across said chamber above

- the bottom, a series of pipes extending a substantially uniform distance upwardly from said plate furnishing overflow passageways, means for heating oil in a substantially continuous stream under pressure to a cracking temperature, means for separating out carbon and residue from said product, means for discharging the balance of said product into said chamber above said plate, a condenser 5 connected to the vapor outlet of said chamber, and means for maintaining substantially uniform vapor pressure in said converting means, carbon separator, chamber and condenser.
- 10 15. Apparatus for converting high boiling hydrocarbon oil into lower boiling products, comprising a furnace, a tubular oil converter therein maintained at a cracking temperature, means for continuously supplying oil to one end of said converter under pressure, means for discharging products at the other end thereof, a carbon and residue collecting device outside of said furnace connected to receive said discharged material, a separating 20 chamber outside said furnace connected with the upper portion of said carbon collecting device and means for separately withdrawing oil and vapors from said separating chamber.
- 25 30. 11. A continuous tubular oil treating apparatus comprising a nest of heating tubes, a chamber connected in circuit with said tubes, a diaphragm in the chamber dividing the same into upper and lower compartments, said diaphragm being provided with open passageways connecting the compartments, the entrance to said passageways in the upper compartment being above the level of said diaphragm, means for continuously supplying liquid to the heating tubes, means for withdrawing liquid from the lower part of the chamber and means for withdrawing vapors from the upper part of said chamber and condensing the same.
- 35 40. 12. A continuous tubular oil treating apparatus comprising a nest of heating tubes connected in series, an enlarged separating chamber, a diaphragm dividing said chamber into compartments, means for continuously supplying oil to said apparatus so as to cause the oil in transit to progressively flow through the heating tubes, a carbon and residue collecting device connected with the discharge end of the heating tubes, a pipe leading from 45 said device to the separating chamber above said diaphragm, means for withdrawing liquid oil from said chamber and means for withdrawing the vapors.
- 50 55. 13. A continuous tubular oil treating apparatus comprising a nest of heating tubes connected in series, an enlarged separating chamber, a diaphragm dividing said chamber into compartments, means for continuously supplying oil to said apparatus so as to cause the oil in transit to progressively flow
- through the heating tubes, a carbon and residue collecting device connected with the discharge end of the heating tubes, a pipe leading from said device to the separating chamber above said diaphragm, means for withdrawing liquid oil from said chamber and returning it to the tubes for retreatment.
- 60 65. 14. Apparatus for converting high boiling hydro-carbon oil into lower boiling products, comprising a tubular oil converter maintained at a cracking temperature, means for supplying oil to said converter at the top, means for discharging products at the bottom, a carbon and residue collecting device connected to said discharge and extending below the point of discharge, means for drawing off the collected residue and carbon in said device, a separating chamber connected to the upper portion of said collecting device to receive the vapors and oil therefrom, means for separately drawing off the converted vapors and liquid oil from said chamber, means for condensing the converted vapors and means for returning the liquid oil to the converter for retreatment.
- 70 75. 15. Apparatus for converting high boiling hydro-carbon oil into lower boiling products, comprising a furnace, a tubular converter in said furnace maintained at a cracking temperature, a source of oil supply, means for continuously forcing oil from said supply under pressure into the upper end of said converter, means for conveying the heated products from the bottom of said converter to a point outside of said furnace, a residue and carbon collecting device into which said products are discharged extending below the point of discharge, a separating chamber at a higher level and connected to the upper portion of said residue and carbon collecting device means for separately and continuously drawing off the converted vapor and liquid oil from said chamber, means for continuously condensing the vapors under pressure and means for continuously returning the liquid oil to the converter.
- 80 85. 16. Liquid phase apparatus for converting high boiling hydrocarbon oil into lower boiling products, comprising a tubular converter maintained at a cracking temperature and a superatmospheric pressure, a carbon and residue-collecting device connected to the end of said tubular converter, a separating chamber connected to said device for separating the evolved vapors from the unconverted liquid oil, means for continuously forcing a stream of oil under pressure through said tubular converter, device and separating chamber and returning the unconverted liquid to said converter for retreatment, and means for withdrawing the separated vapors from said separating chamber.
- 90 95. 17. Apparatus for converting high boiling point hydrocarbon oils into lower boiling products that comprises a single elongated

tubular cracking coil composed of a plurality of pipe sections connected together at their ends in series relation and arranged in vertical tiers of rows or layers one above the other, means for rapidly forcing oil under pressure through said cracking coil, a furnace disposed beneath the cracking coil for heating the coil to raise the oil to a cracking temperature in transit therethrough to be cracked therein, an enlarged unheated zone disposed outside of the furnace in free and open communication with one end of said cracking coil and containing a body of hot liquid oil delivered thereto from said cracking coil, said enlarged zone comprising a lower portion into which the cracking coil delivers the oil and in which heavy residual oil and carbon accumulates and an upper portion into which the hot oil rises, means to establish a liquid level in the upper portion of said zone from which the separation of vapors takes place, a draw-off connected to the lower portion of said enlarged zone for removing heavy residual oil and carbon, and a vapor line connected to the upper portion of said zone above the liquid level for removing the separated vapors.

18. Apparatus for converting high boiling hydrocarbon oil into lower boiling products that comprises an elongated tubular cracking coil composed of a plurality of pipe sections connected together at their ends in series relation, means for forcing oil rapidly through said cracking coil, means for heating said cracking coil to raise the oil in transit therethrough to a cracking temperature, an enlarged unheated collecting chamber disposed outside of the heating zone and connected to the discharge end of said coil in which a body of highly heated oil collects and the velocity of flow is retarded and in which heavy residue and carbon resulting from the cracking operation precipitate, and a vapor separating chamber into which cracked products from the enlarged collecting chamber are delivered comprising an intermediate tray or partition having a plurality of short pipes projecting upwardly therethrough, around which a shallow pool of oil accumulates on the tray and through which vapors from the space below pass in heat-exchange relation to the shallow pool of collected oil on the tray, means for removing the evolved vapors from the space above said pool and means for maintaining superatmospheric pressure on the oil under treatment throughout the apparatus.

In testimony whereof I affix my signature.
JOSEPH H. ADAMS.
